APPARATUS FOR TREATING MATERIALS

Franklin S. Smith, New Haven, Conn.

Application November 4, 1938, Serial No. 238,867

6 Claims. (Cl. 21—102)

This invention relates to an art and apparatus for treating food and other products and is especially concerned with sterilizing products by means of an electrical discharge.

One of the objects of this invention is to provide a thoroughly reliable art and apparatus for subjecting food and other products to a treatment in a dependable and practical manner without injury to the product. Another object is to provide an art and apparatus of the above character in which food or other products may be subjected to an electrical treatment. A still further object is to provide an art and apparatus of the above character wherein food or other products may be sterilized without injuring the product in any manner.

Another object is to provide a highly efficient and thoroughly practical art and apparatus of the above character which may be used to destroy insects or other life, including all eggs, larvae, and pupae. Another object is to provide an art and apparatus in which these various advantages are obtained and the various functions may be readily and efficiently controlled over wide ranges of usage.

Another object is to provide inexpensive apparatus of the above character, small in size and weight, and capable of dependable and safe operation. A further object is to provide apparatus of the above character which is adapted for use with other apparatus where there are limitations as to the available space which the apparatus must occupy. Other objects will be in part obvious and in part pointed out hereinafter.

The invention accordingly consists in the features of construction, combination of elements, arrangements of parts and in the several steps and relation and order of each of the same to one or more of the others, all as will be illustratively described herein, and the scope of the application of which will be indicated in the following claims.

In the accompanying drawings in which are shown some of the various possible embodiments of the electrical and mechanical features of my invention;

Figure 1 is a front elevation of the apparatus, some parts being shown diagrammatically, some parts being broken away, and other parts being shown in section;

Figure 2 is a plan view showing the electrode structure and the path of the material with certain parts broken away;

Figure 3 is a vertical sectional view on the line 4—4 of Figure 1, certain parts being broken

away and others omitted, showing a package in the treatment zone;

Figure 4 is a sectional view of the upper electrode element with the supporting construction and the motor omitted;

Figure 5 is an elevation of a single vertical condenser member;

Figure 6 is an enlarged sectional view of an electrode roller and condenser unit with certain parts broken away;

Figure 7 is a vertical section on the line 7—7 of Figure 6;

Figure 8 is a view with certain parts broken away showing the upper electrode structure and the parts associated therewith; and

Figure 9 is a view similar to Figure 8 but showing a modified form of the electrode construction.

This application is a continuation-in-part of 20 my copending application Serial No. 157,699, filed August 6, 1937, entitled "Method and apparatus for treating materials."

The particular embodiment disclosed herein 25 operates to pass products such as packages of food through a discharge zone where they are subjected to a high potential with the result that discharges take place within the products. When this apparatus is used in a manner explained in detail below, these discharges are of a corona-like 30 disruptive nature and thoroughly treat the entire product. It has been found that high practical and desirable results are thus obtained with apparatus which is light in weight, compact, and economical to build and use.

35 Referring to Figure 1, the apparatus includes upper and lower electrode structures, generally referred to by the numerals 2 and 4, respectively having a discharge zone 3, therebetween. The product being treated is moved through this 40 treatment zone and, at the same time, a high-frequency, high-potential voltage is impressed across the two electrode structures so as to cause a disruptive corona-like discharge through the product.

45 The product being treated enters the machine at the right (see also Figure 2) through opening 5, and leaves the machine at the left through opening 6, thus moving through the machine upon a roller conveyor system which includes a group of dielectric rollers 9 at the right, a group of electrode rollers 10 at the center, and a group of dielectric rollers 11 at the left. As has been 50 explained in my copending application, Serial No. 157,699, movement of the product is obtained by rotating the rollers and the path of

the product may be determined by means such as guide rails of dielectric material positioned above the roller conveyor. In the present embodiment, one pair of guide rails 7 extends (see Figures 1 and 2) from opening 5 over rollers 9 and another pair 8 extends from opening 6 over rollers 11.

Rollers 9 and 11 and electrode rollers 10 are rotatably mounted and are rotated by an endless belt 12 which contacts the underside of each roller 9 and 11 at one end and each electrode roller 10 (see also Figure 3) to the right of the center thereof. Endless belt 12 is carried by pulleys 14 and 16 and is driven through a speed reduction gear unit connected to pulley 14 by a motor 13 (Figure 2).

The upper electrode structure 2 includes a plurality of electrode units which are mounted upon a cylindrical shell construction, generally indicated by the numeral 17, the details of which will be pointed out below. In this embodiment, a group of twenty-one electrode units are evenly spaced along the shell construction 17, one electrode unit, generally indicated at 15, being positioned at each end of the group, and there being nineteen (see also Figure 8) electrode units, generally indicated at 18. Shell construction 17 is rotatable and is provided with two electric motors and a central fixed shaft, the entire structure being supported at the ends by a pair of end brackets 20.

As best shown in Figure 4, each electrode unit 15 is formed by four electrode elements 21 of generally tear-shaped configuration which extend arcuately and are connected together to form a ring surrounding shell construction 17; electrode units 18 are similarly formed by electrode elements 22 having substantially similar configuration to elements 21. The details of construction and assembly will be more fully pointed out below.

Referring again to Figure 3, each of the electrode rollers 10 is formed by a hollow tube of low-power factor glass or fused quartz to the right end of which is attached a metal cap 26 with an integral supporting pin 28. During operation, the gas in each electrode roller 10 ionizes thus forming a conductive path extending along the axis of the electrode roller throughout its length and into cap 26. The left end of each electrode roller cooperates with the upper electrode elements 21 and 22 above it, and there is thus formed a discharge zone in which discharges occur emanating from the electrode elements 21 and 22 above and extending to the electrode rollers 10 below.

As shown best in Figure 1, the entire apparatus is mounted in a casing 30 having legs 32 and sheet metal side walls. The high-frequency, high-potential voltage is produced by apparatus of the type shown in my prior Patent 1,975,805, issued October 9, 1934, and is mounted mainly upon the roof of casing 30; there being at the right a high-frequency, low-voltage alternator 33; at the left a power-factor compensating resonance coil 34 and additional potential regulating means; and in the center a high-voltage auto-transformer 36. A suitable meter and control apparatus is mounted in casing 30 adjacent alternator 33 and includes switches 38 and voltmeter 40.

As explained in my prior Patent 1,975,805 and in my copending application Serial No. 157,699, auto-transformer 36 receives the high-frequency, low-voltage of alternator 33 and transforms this into a high-frequency, high-voltage which is impressed across the upper and lower electrode 70

structures 2 and 4 respectively to produce the disruptive corona-like discharges. One end of the winding of auto-transformer 36 is grounded, and the other end is connected to a lead extending downwardly through terminal 42, and thus, to the upper electrode structure 2. A tap upon the auto-transformer winding is connected to a lead which extends through terminal 44 and through the control mechanism to one of the output leads of alternator 33. The other output lead of alternator 33 is grounded, and thus the output voltage of the alternator is impressed across the portion of the auto-transformer winding between the tap and the grounded end.

15 Mounted below auto-transformer 36 within the same casing is an insulation transformer (not shown) by means of which a suitable voltage is supplied to the motors which rotate the upper electrodes. This insulation transformer has a primary winding connected to a suitable source of alternating current (not shown) through a pair of terminals 43 (only one of which is shown). The secondary winding of the insulation transformer is electrically connected through terminal 42 to the electrode motors and this winding is insulated from its primary winding for a voltage corresponding to the maximum output potential of the auto-transformer.

20 The lower electrode structure is electrically connected to ground through an air condenser construction and in this embodiment this air condenser construction comprises a plurality of vertical condenser members, generally indicated by the numerals 46 (see Figure 5), which cooperate with the back wall of casing 30 (Figure 1). One vertical condenser member 46 is provided for each electrode roller and the electrical connection is made through the supporting shaft 28 (Figure 3). As indicated above, supporting shaft 28 also assists in holding the electrode roller in position, the main support for the electrode roller being to the right of the center thereof, and being in the form of a bridge member 48 (see also Figure 1) of dielectric material such as Bakelite.

25 Positioned upon the top of bridge member 48 is a plate 50 (Figure 3) also of dielectric material which extends to the left and carries a plurality of spacers 52. Spacers 52 are positioned between the electrode rollers and, as shown best in Figure 50 1, are wedge-shaped with concave sides which fit the contour of the adjacent portions of the electrode rollers. The electrode rollers lie upon the upper web of endless belt 12 (Figure 3) which in turn lies upon and slides along plate 50; the right hand end of each roller is held in position by its supporting shaft 28 and the electrode rollers are held in alignment by spacers 52. Thus, when endless belt 12 moves, the electrode rollers rotate together, and material supported by them 55 is passed from one roller to the other through the treatment zone.

60 The center of gravity of each of the electrode rollers is to the left of bridge member 48, and accordingly, as shown best in Figures 5 and 6, the supporting shaft 28 of each of the electrode rollers fits into an inverted-U-groove 54 in its vertical condenser member 46. Attached to the end of each supporting shaft 28 is an anti-friction bearing unit generally indicated by the numeral 56, the details of construction of which are shown in Figure 7. This anti-friction bearing unit includes a spherical stationary member 58 having a removable screw plug 60 and carrying the outer race 59a of a ball bearing unit. The inner race 59b of the ball bearing unit is rigidly

clamped to supporting shaft 28 by means of a stud bolt 62.

In this manner the electrode roller 10 may be easily removed by moving the right end (Figure 6) downwardly and to the left. However, the electrode rollers are held securely in position, and as indicated above, may be easily rotated by endless belt 12 to support the material and move it through the treatment zone. The vertical condenser elements 46 (see Figures 3 and 6) are supported by two horizontal bars 64 which are in turn supported at their ends by a pair of brackets 66 extending from the bottom of the casing 30. Horizontal bars 64 and brackets 66 are of dielectric material such as Bakelite.

Referring again to Figure 1, the upper electrode structure 2 is adjustably supported from the roof of casing 30 in the manner described in detail in my copending application, Serial No. 157,699, there being a main insulator which is formed by cutting segments from a cylinder of insulating material and which has four downwardly extending arms 67. Integral with the lower ends of arms 67 is a ring portion 68 to which is rigidly attached the elongated frame 70 of the electrode structure 2. This connection between ring portion 68 and elongated frame 70 is by means of two arcuate brackets 72 (see also Figure 2) which carry two horizontal bars 74 having the brackets 20 upon their ends. Thus, a rigid support is provided for the upper electrode structure and the position of the electrode structure may be changed by means of the adjustable support for the main insulator.

As pointed out above, the electrode units 15 and 18 are rigidly mounted upon the cylindrical shell construction 17 and, as shown best in Figure 4, are secured in place by set screws 76. Each electrode unit 15 comprises four electrode elements 21, and each electrode unit 18 comprises four electrode elements 22. The electrode elements of each unit are evenly spaced around the shell construction 17, and, as the electrode unit rotates, these various elements successively move to the lower position so that discharges occur therefrom. The electrode units are also evenly spaced axially along the shell construction, and are spaced arcuately and so positioned that the effective discharge areas of the electrode elements are positioned on nested substantially helical lines along the axis of rotation (see also Figure 3). Eight helical lines are formed by spacing the electrode elements of alternate electrode units in alignment along one set of lines, and then spacing the electrode elements of the intermediate units along another set of lines which are spaced respectively 45° from the first set of lines. Each of the lines extends the full length of the shell construction 17 and extends substantially 45° arcuately.

As pointed out above, there are illustratively nineteen electrode units 18 and two electrode units 15 making a total of twenty-one electrode units. Accordingly, the electrode elements of units 15 and those of nine of the electrode units 18 are positioned along one set of helical lines. This relationship is best shown in Figure 3, where one unit 15a appears in the right foreground and the other unit 15b appears in the left background; the electrode elements of the nine even numbered electrode units 18, that is, the second, fourth, sixth, etc., units, are in alignment with the respective electrode elements of units 15a and 15b.

Spaced arcuately 45° from the electrode ele- 75

ments of unit 15a are the electrode elements of the first unit 18, and in a like manner, spaced arcuately 45° from the electrode elements of unit 15b are the electrode elements of the nineteenth unit 18; the electrode elements of the odd numbered units 18, that is, the third, fifth, seventh, etc., units, are positioned along lines extending between the respective electrode elements of the first and nineteenth units 18. With this spacing of the electrode elements, the rotating electrode construction is properly balanced from a mechanical standpoint, and accurate control is maintained on the discharges so that treatment is uniform throughout the treatment zone.

15 The details of the mounting means for the upper electrode structure are best shown in Figure 8 wherein a rigid shaft extends between the end brackets 20 and carries the stationary elements of the two electrode motors as well as the shell construction 17. The shaft is formed by a cylindrical center portion and two end portions which are received in hubs extending inwardly from end brackets 20. The shell construction 17 is supported adjacent its two ends on the shaft by a pair of roller bearings units 78, each of which is mounted as shown at the right with its inner race clamped to the shaft, and the outer race clamped to the shell construction. The shell construction comprises an elongated shell 80 which is provided at each of its ends with a cylindrical supporting frame member 82 and an end ring 84.

20 The electrode motors are of the squirrel-cage type with a wound stator 86 mounted upon the shaft and a rotor 88 mounted upon the shell. Each of the rotors is held by a retaining ring 92 against an inwardly extending flange 90 integral with the shell 80. Retaining rings 92 are secured in place by set screws (not shown) extending inwardly from the shell. At each end of the shell, the end ring 84 and the frame member 82 are held in position by a plurality of screws 94 extending into tapped holes in the retaining ring 92.

25 40 As shown best at the right of Figure 8, each of the stators 86 is clamped against a ring 96 by a flanged nut 98, the flange of which extends over the edge of the stator winding to provide a shield. The left hand end of the winding is protected by a similar shield 100. A collar 102 is fitted against nut 98, and the inner ring of the ball bearing unit is clamped against this collar by a nut 104 which is provided with a suitable lock washer.

30 45 50 As indicated above, the entire upper electrode construction including the horizontal bars 74 and the end brackets 20 are maintained at the potential of the upper electrode elements. In order to avoid undue concentration of flux, the entire structure is shielded to avoid sharp corners from which disruptive sparks might emanate. Accordingly, each of the end brackets 20 is provided with a shield 108, and the ends of horizontal bars 74 are covered by shields 110. In addition to this and in order to obtain more accurate control of the discharges at the ends of the treatment zone, the end electrode units 15 comprise electrode elements 21 which are wider than the electrode elements 22, and the curvature is less at their effective discharge surfaces; thus, excessive flux concentration is avoided.

55 60 65 70 75 Each of the stators 86 is provided with a main winding and a starting winding, and each of the starting windings has connected in series therewith a condenser which is positioned in the ad-

jacent end bracket 20 and protected by the shield 108. As indicated above, power is supplied to the electrode motors through an insulation transformer positioned below the high-potential transformer and in the same casing. One side of the secondary winding of this insulation transformer is connected to the high-potential lead running from the high-potential transformer to the electrode structure. This lead is electrically connected to the supporting frame, and one side of the main and starting windings of each electrode motor is also electrically connected to the supporting frame. The remaining side of the secondary winding of the insulation transformer is in turn electrically connected to the remaining sides of each of the motor windings through suitable leads, the connections to the starting windings being through the respective condensers.

In order to insure the maintenance of a good electrical connection from the rotating electrode structure to the supporting frame, and thus with the high-potential side of the high-potential transformer, two spring pressed brushes 112 are provided, one of which extends inwardly from each of the end brackets 20. Each brush 112 rides upon a washer-shaped collector ring 114 which is rigidly held to its end ring 84 by a plurality of screws 116. Collector rings 114 snugly fit the supporting shaft and thus effectively prevent the entry of foreign materials to the interior of the shell construction.

The details of construction of the vertical condenser elements 46 are best shown in Figures 5, 6, and 7. The main portion of the element is a flat, metal tube, and this is reinforced at the points of support and at the inverted-U-slot 54. Concentration of flux at the ends of the tube is prevented by a pair of shields 115. Each condenser element is supported by a pair of studs 118, one of which extends to each of the horizontal supporting bars 64. With the condenser electrode unit shown in Figure 6, these studs are positioned at the tops of the horizontal bars 64, and alternate condenser elements are supported in this manner, but, as shown in Figure 1, the intermediate condenser elements are supported by struts positioned at the bottom of these horizontal bars. Thus, referring to Figure 3, there is a stud 118 positioned at the top of each of the bars 64 and connected to the nearest or first condenser element, and there is another stud 118 at the bottom of each of the horizontal bars which is connected to the second condenser element.

As indicated above, the electrode rollers 24 are formed of tubes of dielectric material such as low power-factor glass or fused quartz, and these tubes are filled with neon gas. During operation, this gas is ionized, and thus forms an electrical path along the axis of the electrode roller. The discharges occur between the upper electrode structure 2 and the upper surface of the electrode rollers, each electrode roller cooperates with its condenser element to form an operating electrode-condenser unit. In order to maintain uniform conditions throughout the treatment zone, it is important that the various electrode-condenser units have substantially uniform electrical characteristics.

There are variations in the thickness of the walls of the various dielectric tubes, and at times it has been difficult to compensate electrically for these variations. However, the electrical connection between the electrode roller and its

condenser element is completed through cap 26 (Figures 3 and 6) which is fitted over and electrically connected with a metallic coating 120 upon the surface of the dielectric tube.

During operation, this metallic coating 120 forms one plate of a condenser, the other plate of which is formed by the ionized gas within the electrode roller; this condenser is thus electrically in series with the ionized gas. The capacitance of this condenser may be varied by changing the surface area of the metallic coating 120; in this manner, each condenser is given a value dependent upon the wall thickness of the particular dielectric tube. Thus, the variations in the wall thickness of the various tubes are individually compensated for, and the electrical characteristics of the various operating units are made uniform.

In the manufacture of these electrode rollers, the entire dielectric tube is ground to a uniform diameter, and then the metallic coating 120 is applied by means of a metal spray gun, the metallic coating in this embodiment being solder. Subsequently, the surface of the metallic coating 120 is accurately ground to fit the inner surface of cap 26; cap 26 is then properly positioned and soldered in place. During these operations, the series capacitance of the electrode roller is measured and is adjusted to a predetermined value by varying the surface area of the metallic coating 120 and the length of cap 26.

In the modified embodiment of the upper electrode structure shown in Figure 9, the electrode elements 218 are toroidal, and they are mounted upon the shell construction 17 in a manner similar to that of electrode elements 15 and 18. The electrode elements 218 snugly fit the shell 17 and are held securely in place by spacer collars 222; spacer collars 222 are held rigid to shell 17 by set screws 224. At each end of shell 17, a flanged end ring 226 holds the adjacent electrode element in place. Illustratively, there are fourteen electrode elements 218, the seven electrode elements at the right being spaced 180° radially from the seven at the left. Each electrode element is provided with a discharge surface 220 which is toroidal in shape with its axis at an angle to the axis of rotation. The discharges between the lower electrode structure and each of the electrode elements 218 are at all times concentrated at the portion of the discharge surface 220 which is at the bottom, and this shall be referred to as the "active discharge surface."

With one of the electrode elements in the position shown at the left of Figure 9, the active discharge surface is at the right limit; and after the rotating electrode structure moves through 180°, this electrode element will be in the position of the electrode element shown at the right of Figure 9; during this movement, the active discharge surface moves to the left limit. Subsequently, as the electrode structure continues to rotate, the active discharge surface moves back and forth between its limits. The electrode elements 218 mounted at the right of the shell construction operate in a similar manner, but the active discharge zone is always moving in the opposite direction.

The ends of the electrode construction are shielded by a pair of shields 208, and the horizontal bars 74 are shielded by a plurality of shields 110 in the manner of the preferred embodiment (Figure 8). The electrode motors and their operation may be similar to that of the preferred embodiment.

As many possible embodiments may be made of the mechanical features of the above invention and as the art herein described might be varied in various parts, all without departing from the scope of the invention, it is to be understood that all matter hereinabove set forth or shown in the accompanying drawings is to be interpreted as illustrative and not in a limiting sense.

I claim:

1. In electrical treating apparatus, an electrode roller comprising, a gas filled tube of dielectric material, and an electrical contact and mechanical supporting construction for said tube comprising a metallic coating upon one end of said tube and a cylindrical shell in intimate contact with said coating and having a pivot extending therefrom, the gas within said tube when ionized forming an extended electrode surface and being electrically connected through said metallic coating and said shell to said pivot.
2. In apparatus of the class described, an electrode roller-condenser construction comprising, an electrode roller adapted to extend horizontally into the treatment zone and support the material being treated, means positioned within said roller to provide an electrical conducting path along the axis of said roller, and a vertically extending condenser element positioned adjacent said electrode roller and mechanically and electrically connected thereto, said condenser element comprising a flat tubular member with enlarged end portions.
3. In apparatus of the class described, an electrode roller-condenser construction comprising, an electrode roller adapted to extend horizontally into the treatment zone and support the material being treated, means positioned within said roller to provide an electrical conducting path along the axis of said roller, and a verti-

40
5
cally extending condenser element positioned adjacent said electrode roller and mechanically and electrically connected thereto, the electrical connection between said electrode roller and said condenser being by means of a metallic cup at the end of said electrode roller.

4. In electrical apparatus of the character described, the combination of: a sealed tube of dielectric material containing material capable of 10 acting as an electrical conducting medium and capable of forming one plate of a connecting condenser element; and means providing support for the tube and also forming the other plate of the connecting condenser element comprising, 15 a surface-covering material upon the exterior surface of said tube, and a rigid support means extending about said surface-covering material.
5. In electrical treating apparatus, a condenser construction formed by a pair of condenser-plate structures positioned in cooperating relationship, one of said condenser-plate structures comprising a plurality of elongated elements which are substantially flat with enlarged end portions, each of said elongated elements having one of 20 25 its extended surfaces as its active condenser surface and said elongated elements being positioned with all of the active condenser surfaces substantially in a single plane.

6. In electrical apparatus of the class described, the combination of: a sealed tube of dielectric material containing material capable of acting as an electrical conducting medium and capable of forming one plate of a connecting condenser element; a metallic shell structure 30 35 intimately contacting the surface of the tube and forming the other plate of the connecting condenser element; and a rigid support means mechanically connected to said shell structure.

FRANKLIN S. SMITH.
